UNITED STATES PATENT OFFICE.

NORBERT M. LA PORTE, OF BALTIMORE, MARYLAND.

CIRCULATING SYSTEM.

1,138,962.

Specification of Letters Patent. Patented May 11, 1915.

Application filed December 9, 1914. Serial No. 876,184.

To all whom it may concern:

Be it known that I, NORBERT M. LA PORTE, a citizen of the United States of America, residing in the city of Baltimore, State of Maryland, have invented certain new and useful Improvements in Circulating Systems, of which the following is a specification.

This invention relates to a new and improved means for circulating or accelerating the circulation of the water used for cooling the cylinders in internal combustion engines.

The device is described and shown in connection with an automobile engine though it is capable of various applications as to marine or stationary engines.

The great majority of motor cars in use at the present time are driven by internal combustion engines, cooled by means of water which passes through a cylinder jacket and then through a radiator in the front of the machine. In a great many of these cars, dependence is had for circulation on the so-called thermo-siphon or gravity system but in a multitude of cases, this is found insufficient and the purchasers of cars so equipped often find it necessary to provide a circulating pump. This is placed at some convenient point in the radiator connections and usually driven by a belt or chain from the fan shaft or other moving part. A great many of these pumps are constructed and sold with the idea that they shall be installed by the owner or chauffeur of the car to be equipped. The device herein described is convenient, simple and inexpensive and adapted to be sold to the same class of trade. To apply it, it is only necessary to remove one of the connections from the circulating system and replace it with a corresponding length of pipe furnished with the applicant's pump, at the same time boring a small hole in the exhaust manifold in which a plug carrying a small pipe coupler is inserted. With these two operations, the installation of the applicant's device is complete. In one well-known type of car using the thermo-siphon

system of circulation, two hose couplings and an intermediate radiator pipe in the connections offer a convenient opportunity for the installation of this pump. It is only necessary to loosen the hose couplings, remove the pipe and insert applicant's pump

in place of it, tighten the hose couplings again, and then make the exhaust connection.

Broadly stated, the invention relates to the use of a gas nozzle in the radiator connection proper, the nozzle being turned in the direction of circulation and fed by the exhaust. In its preferred form the cooling water circulating pump which is the subject of this invention, consists of a length of pipe to be substituted for a part of the radiator connection, the pipe having a reduced portion or nozzle corresponding to the nozzle of an injector, a gas nozzle or outlet in the water nozzle and suitable connections from the gas nozzle to the exhaust manifold, both nozzles being turned in the same direction, preferably that of the flow of the cooling water under normal conditions.

As has been stated, the use of a mechanical pump installed at almost any convenient point in the system and connected in various ways to the moving parts of the engine is well known, some of the advantages of the applicant's device being its simplicity, cheapness and convenience of installation and greater length of life, as compared to these various mechanical pumps. It is also important to note that with this system, the circulating and hence the cooling effect is proportionate or directly related to the heating effect for the more the power required, the greater the amount of fuel burned and the greater the exhaust pressure and circulating effect, whereas with the mechanical pumps, the circulating and cooling effect is proportionate to the speed of the engine which in turn bears no direct relation to the heating effect.

In the accompanying drawing, I have illustrated so much of the cooling water-circulating system of an automobile to which the device of my invention has been applied as is necessary to a full and complete understanding of the invention.

Figure 1 is a side elevation of a motor, radiator connections and circulating pump; and Fig. 2 is a section through the pump or barrel.

Referring to the drawings by numerals, each of which is used to indicate the same or similar parts in the different figures, the illustration includes an internal combustion motor 1 having a water jacket 2, a radiator 3 with top connections 4 and bottom connections 5.

tions 5 from the jacket to the radiator and vice versa.

In the form in which the motor is shown, the bottom connection includes two hose couplings 6 and 7 with an intermediate pipe. In the present instance, this pipe or any suitable portion of the radiator connections is replaced by a pump member 8 including a water nozzle 9 and a gas nozzle 10, the two 10 being preferably concentrically placed and disposed in the same direction, which is the direction of the normal circulation of the water, and the exhaust manifold is tapped at any convenient point, as that indicated by 15 reference character 11, for the installation of the tube 12 or rather a suitable fitting 13 to which the end of the tube is attached by means of a packed joint 14 or the like. Incidentally, this fitting may include a seat for 20 a non-return valve 15 which serves to prevent the escape of water into the exhaust manifold either when the engine rocks backward in starting or stopping, or when the engine is idle and the cooling water in the 25 radiator flows backward through the gas tube 12. Also, to prevent, as far as possible, the transmission of the pulsations of the exhaust to the gas nozzle 10, which might cause hammering in the radiator, an expansion or accumulator chamber 16 is provided 30 in the pipe 12. This should be made of a size sufficient to practically eliminate pulsation at the nozzle and may be approximately equal to the volume of the tube. As an additional means for preventing flow of the 35 cooling water to the exhaust manifold either with or without the check valve 15, I provide an air trap at 18 by carrying the tube 12 above the level of the water in the radiator 40 so that when the engine is idle and the exhaust pressure ceases, the water cannot back through the tube 12 to the exhaust manifold.

In the operation of the device, circulation due to the variation in density of the water 45 corresponding to the temperature, will take place when the engine is running, the heated water passing upward from the jacket through the connection 4 to the radiator and thence passing downward as it is cooled 50 and back through the connection 5 to the jacket to replace the water which passes into the radiator. As has been stated however, this method of circulation is found insufficient to cool the engine and to assist the 55 gravity or thermo-siphon action, the applicant utilizes the velocity of the exhaust gases and to this end provides the coöperating water and gas nozzles just described, both being turned in the direction of circulation. 60 While we have shown them in the lower radiator connection, they may be placed at any convenient point in the system. Both nozzles are submerged and placed directly in the radiator connection without any air chamber or cushion or the like and the water 65

nozzle may be dispensed with using merely the velocity of the gas to accelerate the circulation of the water.

When the engine starts, a small portion of the exhaust gases is fed through the pipe 70 12 to the expansion chamber and thence in a comparatively steady stream through the nozzle 10 to the water passage in the vicinity of the contracted portion of nozzle 9. The velocity of the gas, either with or without the nozzle 9 is transferred to the water and the flow thus accelerated. The effect of the contraction of nozzle 9 is to accentuate this action giving a result similar to that obtained by means of a steam injector. If desired, a plug valve 19 may be inserted in the gas pipe so that it is possible to reduce the speed of circulation in cold weather or when cooling in the radiator is excessive. The gas escapes from the radiator through the 85 outlet provided for the escape of steam.

The prevention of back flow has been fully explained.

I have thus described a circulating system embodying my invention in minute detail 90 in order that its nature and operation may be fully understood. However, the specific terms herein are used in their descriptive rather than in their limiting sense and the scope of the invention is defined in the 95 claims.

I claim—

1. An automobile accessory in the form of a circulating pump consisting of a tubular member to be used as a substitute for the 100 radiator connection which extends upward from the bottom of the radiator to the water jacket, the said tubular member having a reduced portion forming a water nozzle disposed toward the water jacket, a gas nozzle 105 coöperating with and directed into the water nozzle, and means connecting the gas nozzle to the exhaust manifold, the water nozzle and gas nozzle having an injector action and serving to lift the water and carry it from the bottom of the radiator to the water jacket and thus accelerate the circulating action.

2. An automobile accessory consisting of a radiator connection to act as a circulating 115 pump, the said connection having a reduced portion forming a water nozzle directed toward the water jacket, a gas nozzle coöperating with and turned in the direction 120 of the water nozzle, a small tube for connecting the gas nozzle to the exhaust manifold, a chamber forming part of the passage between the gas nozzle and manifold for equalizing the pressure of the exhaust gases before they reach the nozzle, and means for 125 preventing flow of the cooling water to said gas nozzle.

3. A water cooling system for internal combustion engines consisting of a water jacket, a radiator and connections arranged 130

to give thermosiphonic circulation including means connecting the bottom of the radiator to the water jacket, the said connection being in the form of a pipe to act as a circulating pump, a gas nozzle in the pipe turned in the direction of thermosiphonic circulation, the pipe being reduced as to its internal dimension just beyond said gas nozzle, a tube for leading a portion of the exhaust gases to said nozzle, and means for preventing back-flow of water through said tube.

4. A water cooling system for internal combustion engines consisting of a water jacket, a radiator and connections arranged

to give thermosiphonic circulation including a pipe connecting the bottom of the radiator to the water jacket, a gas nozzle in the said pipe turned in the direction of thermosiphonic circulation, a tube for leading a portion of the exhaust gases to said nozzle, and means for preventing back-flow of water through said tube.

Signed by me at Baltimore, Maryland, this 3d day of December, 1914.
